(57) **CLAIM**

I claim the ornamental design for a bracelet representing the down syndrome genome, as shown and described.

DESCRIPTION

FIG. 1 is a perspective view of a bracelet representing the down syndrome genome, showing my new design;

FIG. 2 is an enlarged top plan view thereof;

FIG. 3 is an enlarged bottom plan view thereof;

FIG. 4 is a left-side elevational view thereof, the right-side elevational view being a mirror image thereof;

FIG. 5 is a front elevational view thereof; and,

FIG. 6 is a rear elevational view thereof.

The broken lines showing a person's wrist in FIG. 1 depict environmental matter and form no part of the claimed design.
